UNITED STATES PATENT OFFICE.

GEORGE F. LYMAN, OF KNOXVILLE, TENNESSEE.

TIPPLE.

1,070,149.

Specification of Letters Patent.

Patented Aug. 12, 1913.

Application filed October 28, 1911, Serial No. 657,384. Renewed May 31, 1913. Serial No. 771,083.

To all whom it may concern:

Be it known that I, GEORGE F. LYMAN, a citizen of the United States, residing at Knoxville, in the county of Knox and State of Tennessee, have invented a new and useful Improvement in Tipple, of which the following is a specification, reference being had to the accompanying drawing.

My improvement relates particularly to tipples used for dumping or discharging loads from mine cars, contractors cars, and similar small cars.

The object of the improvement is to provide a tipple which may be detachably applied to any portion of a railroad track of proper gage to operate the cars which are to be dumped, the construction of the tipple being such as to permit dumping over either side or over the end of such a track. The mechanism comprises means for engaging the rails of such railroad track at any point on the latter, so that the tipple may be placed upon such track and moved from place to place upon said track and secured at each such place to said rails and operated at such place as long as desired. Such track need not be specially constructed nor provided with any attachment to adapt it to receive the tipple; and when the tipple has been detached from the track and removed to another place on the track or removed altogether from said track, the latter is left precisely as it was before the tipple was brought to such place and there secured to said track. In view of these facts, said tipple may be regarded as a temporary attachment to said track. For convenience in description, said track is herein termed the fixed track while the track section on the tipple is called the tipple track. But such term, "fixed", is to be regarded as relative only; for the track to which the tipple is attached may be portable. It is usually fixed while the tipple is used thereon.

The apparatus comprises a horizontal, flat base which is placed upon and secured to the track rails at approximately the level of the latter; and upon said base is a flat turn-table bearing a tipple track section comprising rails which rest above the track rails and preferably have both ends of each sloping downward to approximately meet the track rails. Upon each such rail is a horn or stop member for engaging the car against forward movement. Said horns or stop members are adapted to be moved out of the

range or path of said car when it is desired to allow the latter to pass from the tipple track to the fixed track when said turn-table is in such position as to bring said tracks into alignment with each other.

The tipple track rails are preferably joined to each other to form a tipple track section, and said section is preferably hinged to the turn-table for tilting said section on a horizontal axis, as will be hereinafter described.

My improvement does not include the broad features of such a tipple, but relates to certain details of construction as will be indicated by the claims hereto appended.

In the accompanying drawings, Figure 1 is a plan of a tipple embodying my improvement; Fig. 2 is a side elevation; Fig. 3 is a section on the line, 3—3, of Fig. 1 looking toward the left; Fig. 4 is a section on the line, 4—4, of Fig. 1 looking toward the left, the tilting track section being in the inclined position and moved to the position shown in dotted lines in Fig. 1 and the rear portion of said track section being broken away; Fig. 5 is a bottom view; Fig. 6 is a section on the line, 6—6, of Fig. 1 looking toward the right; Fig. 7 is a section on the line, 7—7, of Fig. 1 looking toward the right, the hook which is shown in elevation being in engagement with an adjacent lever.

Referring to said drawings, A, A, are two ordinary fixed track rails resting upon ordinary ties, B, B. Each such track rail has the usual head, a. A flat, rectangular tipple base, 1, rests upon the two rails, A, A, said base being a flat metal plate approximately square and having two opposite edges resting upon the rails, A, A. Said base is secured to said rails by means of two horizontal bars, 2, hinged to the bottom of the base and extending from one rail to the other and being long enough to cause their ends to extend beneath the heads of the rails, A, A. The hinges for said bars are formed on upright studs, 3, extending downward from the base. For moving the bars, 2, simultaneously, a connecting bar, 4, is placed parallel to and adjacent each track rail, A, A, and coupled to the bars, 2. At one end of said bars, a handhold section, 5, is hinged to said bar at 6, while a similar handhold section, 5, is applied in the same manner to the diagonally opposite end of the connecting bar, 4. Pulling either of said hand-holds away from the base will turn said bars, 2, slant-

wise upon their journals or studs, 3, so that the ends of said bars will move outward from beneath the heads, *a*, of the track rails, A, A. Pushing either hand-hold toward the base will turn said bars, 2, in the opposite direction and bring them transverse to the rails, A, A, and cause the ends of said bars to extend beneath the heads of said rails. Stationary stop lugs, 7, extend 10 downward from the lower face of the base into the paths of the bars, 2, to limit the movement of said bars. When the hand-holds, 5, are not used they turn by gravity on their hinges, 6, until the free ends of said hand-holds rest on an adjacent tie or on the track ballast. Upon the base thus secured to the fixed track is a circular upward 15 extension, 8, the center of which is coincident with the center of the base, 1. Said upward extension may or may not be integral with the base. Above said extension, 8, is a rectangular turn-table plate, 9, of approximately the dimensions of the base, 1, and having its center coincident with the center 20 or axis of the circular upward extension, 8. A flat turn-table ring, 10, surrounds the circular extension, 8, and is secured flatwise against the lower face of the turn-table plate, 9. Said ring may or may not be integral with said plate. A king bolt, 11, extends upward through the base plate, 1, circular extension plate, 8, and the turn-table plate, 9, on the axial line of said members. A key or cotter, 12, extends through the 25 upper end of said king bolt to retain the latter in position.

Upon the turn-table plate, 9, are two hinge bars, 13, one of said bars being adjacent one edge of the turn-table plate 30 while the other of said bars is adjacent to the opposite edge of said plate. Said bars project horizontally beyond one edge of said plate and each such projecting end has a horizontal bearing, 14. Said bearings are 35 in alinement with each other and support a horizontal shaft, 15, each end of which projects beyond the adjacent bearing.

Directly above each fixed track rail, A, A, is a tilting tipple track section rail, 16, which rests beside the adjacent hinge bar, 13, and upon the upper face of the turn-table plate, 9. Each end of each rail, 16, is tapered and inclined or sloped downward to or toward the adjacent fixed track rail, A. 40 Opposite each bearing, 14, on the hinge bar, 13, each rail, 16, has a downward extension, 17, in which is a horizontal bearing, 18, in alinement with the bearings, 14. Each 45 end of the shaft, 15, extends through the adjacent bearing, 18, and is secured against endwise movement by a key or cotter, 19, extending through said shaft. And said cotter serves to hold the tipple rails, 16, against the adjacent ends of the hinge bars, 13. The 50 opposite ends of the rails, 16, are spaced by

means of a space bar, 20, located between and extending through said rails and having a shoulder, 21, at the inner side of each rail and a nut, 22, at the outer side of each rail. Said rails are further spaced and secured to each other by means of a transverse bridge bar, 23, extending transversely beneath said rails and having each end secured to the adjacent rails by means of a rivet or bolt, 24.

On the outer side of each tipple rail, 16, between the horizontal shaft, 15, and the adjacent inclined portion of said rail are two horizontal ears, 25, 25, having horizontal bearings, 26, parallel to the rail. Through 70 each pair of said bearings extends a rock shaft, 27. Said shaft also extends through an ear, 28, located on the same side of the rail at the opposite side of the turn-table. In front of each forward ear, 25, a collar 75 29, surrounds the adjacent shaft and is immovably secured thereto by a set bolt, 30, to hold the shaft against rearward movement. Between the ears, 25, the hub, 31, of a horn or stop, 32, surrounds each shaft, 27, 80 and is secured immovably to the latter by means of set bolts, 33, so that when said shafts are rotated, said horns must also rotate. Adjacent each of the ears, 28, a forked arm, 34, is secured to the shaft, 27, in any 85 suitable manner. The drawings show the shaft extending through one end of said arm and a set bolt, 35, extending through the arm and bearing against the shaft to bind the arm immovably upon the shaft. 90 Each such arm is directed downward and outward (see Fig. 6) and has coupled to its free end one end of one of two horizontal link bars, 36, 36, the other end of such link bar being coupled to a horizontal link bar 95 lever, 37, which is pivoted to the transverse bridge bar, 23, midway between the two tipple track rails, 16, to move in a horizontal plane (see Figs. 1 and 5). One of the link bars, 36, is joined to the link bar lever, 37, 100 at one side of the pivot of the latter, while the other of said link bars is joined to said lever at the opposite side of said pivot, so that when said lever is moved, one of said link bars is moved endwise in one direction 105 while the other of said link bars is moved endwise in the opposite direction, in order that the lower end of the arms, 34, may be simultaneously drawn toward each other or simultaneously pushed from each other. 110 Since the arms, 34, are rigidly joined to the shaft, 27, it follows, that the movement of the link bar lever, 37, will cause the rocking or partial rotation of the shafts, 27, in opposite directions. A contracting coiled spring, 115 38, has one end joined to the lever, 37, while its other end is joined to the adjacent track section rail, 16, by an ear, 39. Each horn or stop, 32, has a heel or base, 40, which rests 120 upon the adjacent rail, 16, when the horn is 125 130

in its upright and working position. The various parts are of such relative dimensions and arrangement as that when the lever, 37, is free to respond to the action of the spring, 38, said lever may be turned in the proper direction to push the arms, 34, outward and upward and rotate the shaft, 27, in the proper direction to turn the horns upward until said base bears upon the rail, 16, the action of said spring then holding said horns in said position.

When the horns or stops are to be turned out of the upright position, the lever, 37, is turned against the action of said spring, whereby the link bars, 37, are drawn so as to turn the arms, 34, downward and inward, whereby the shafts, 27, are rotated so as to turn the horns outward. To engage the lever, 37, and hold it immovably when the horns have been thus turned outward, a hook, 41, is hinged to the appropriate rail, 16, at 42, and is made of proper length to reach over and engage said lever when the latter is in the position above indicated (see Figs. 1, 5 and 7).

In operation, the tipple is placed upon the track from which material is to be dumped. Any portion of the track may be selected. The bars, 2, under the base, 1, are turned so as to cause them to engage the track rails, A, A, as above described. Then the tipple is ready for use. The hook, 41, being released, the horns or stops, 32, automatically assume the upright position upon the tipple track rails, 16, so as to stand in the path of the front wheels of a car entering upon the tipple from the opposite end of the latter. A car thus entering upon the tipple meets and moves forward upon the sloping rear ends of the rails, 16, thus leaving the permanent track rails, A, A. When the forward wheels of the car have met and engaged the horns, 32, the turn-table is turned upon the base so as to bring the forward end of the car to the side of the track at which the material in the car is to be dumped. If the tipple is set on the end of a track, it need not be turned. When ready for dumping, the rear end of the tilting track section of the tipple is raised, said section turning upon the shaft, 15. Said section is tilted far enough to cause the discharge of the material from the car; and then said section is returned to the horizontal position. If the empty car is to then go forward away from the tipple to make room from another car to come upon the tipple from the rear, the lever, 37, is turned against the action of the spring, 38, to cause the horns, 32, to move outward into the horizontal position and out of engagement with the wheels of the car. At such time, the lever, 37, may be held by the hand until the empty car has been moved away, or said lever may be temporarily engaged by the hook, 41.

I claim as my invention:

1. In a structure of the nature described, the combination of a base adapted to rest on track rails, means for locking the base to said track rails, a turn-table on said base, rails located on and hinged to said turn-table, and stops hinged to said rails between the ends of the latter, substantially as described. 70

2. In a structure of the nature described, 75 the combination of a base adapted to rest on track rails, means for locking the base to said track rails, a turn-table on said base, tipple rails located on said turn-table, stops hinged to said tipple rails between the ends 80 of the latter, and means extending parallel to said rails for turning said stops, substantially as described.

3. In a structure of the nature described, 85 the combination of a base adapted to rest on track rails, means for locking the base to said track rails, a turn-table on said base, rails located on and hinged to said turn-table and having both ends sloping downward, and stops hinged to said rails between 90 the ends of the latter, substantially as described.

4. In a structure of the nature described, 95 the combination of a base adapted to rest on track rails, means for locking the base to said track rails, a turn-table on said base, tipple rails located on said turn-table, stops hinged to said tipple rails and having heels adapted to rest on said rails when the stops are in the upright position, and means for 100 turning said stops into and out of the upright position, substantially as described.

5. In a structure of the nature described, 105 the combination of a base adapted to rest on track rails, means for locking the base to said track rails, a turn-table on said base, tipple rails located on said turn-table, rock shafts supported by said rails, stops supported by said shafts for their simultaneous partial rotation, substantially as described. 110

6. In a structure of the nature described, 115 the combination of a base adapted to rest on track rails, means for locking the base to said track rails, a turn-table on said base, tipple rails located on said turn-table, rock shafts supported by said rails, stops supported by said shafts in proper relation to be turned into and out of the path of a car traversing said tipple rails, and means for normally holding said shafts in position to 120 place said stops into said path, substantially as described.

7. In a structure of the nature described, 125 the combination of a base adapted to rest on track rails, means for locking the base to said track rails, a turn-table on said base, tipple rails located on said turn-table, rock shafts supported by said rails, stops supported by said shafts in proper relation to be turned into and out of the path of a car 130

traversing said tipple rails, means for normally holding said shafts in position to place said stops into said path, and means for holding said shafts in position to place said stops out of said path, substantially as described.

In testimony whereof I have signed my

name, in presence of two witnesses, this 21st day of October, in the year one thousand nine hundred and eleven.

GEORGE F. LYMAN.
